United States Patent Office

Des. 187,249
Patented Feb. 16, 1960

187,249

AIRPLANE

Gordon E. Codding, Lawndale, Calif.

Application August 11, 1958, Serial No. 52,150

Term of patent 14 years

(Cl. D71—1)

FIG. 1

FIG. 2

Fig. 1 is top plan view of an airplane embodying my new design;

Fig. 2 is a front elevational view thereof;

Fig. 3 is a side elevational view of the airplane; and
Fig. 4 is a perspective view thereof.

The dominant feature of the design resides in the portions shown in full lines.

I claim:

The ornamental design for an airplane, as shown and described.
